U.S. Appl. No. 13/911,068, filed Jun. 5, 2013, Kent C. Erickson et al.

DESCRIPTION

FIG. 1 is a first perspective view of one embodiment of the conduit removal tool according to our new design;

Primary Examiner — George D Kirschbaum

Assistant Examiner — Jennifer Watkins

(74) *Attorney, Agent, or Firm* — Austin Rapp & Hardman

(57) **CLAIM**

The ornamental design for a conduit removal tool, as shown and described.

FIG. 2 is a second perspective view of the embodiment of the conduit removal tool shown in FIG. 1;

FIG. 3 is a rear view of the embodiment of the conduit removal tool shown in FIG. 1;

FIG. 4 is a top view of the embodiment of the conduit removal tool shown in FIG. 1;

FIG. 5 is a front view of the embodiment of the conduit removal tool shown in FIG. 1;

FIG. 6 is a first side view of the embodiment of the conduit removal tool shown in FIG. 1;

FIG. 7 is a second side view of the embodiment of the conduit removal tool shown in FIG. 1;

FIG. 8 is a bottom side view of the embodiment of the conduit removal tool shown in FIG. 1;

FIG. 9 is an enlarged view of the area identified by the reference numeral 9 in FIG. 5;

FIG. 10 is a first perspective view of another embodiment of the conduit removal tool according to our new design;

FIG. 11 is a second perspective view of the embodiment of the conduit removal tool shown in FIG. 10;

FIG. 12 is a rear view of the embodiment of the conduit removal tool shown in FIG. 10;

FIG. 13 is a top view of the embodiment of the conduit removal tool shown in FIG. 10;

FIG. 14 is a front view of the embodiment of the conduit removal tool shown in FIG. 10;

FIG. 15 is a first side view of the embodiment of the conduit removal tool shown in FIG. 10;

FIG. 16 is a second side view of the embodiment of the conduit removal tool shown in FIG. 10;

FIG. 17 is a bottom side view of the embodiment of the conduit removal tool shown in FIG. 10; and,

FIG. 18 is an enlarged view the area identified by reference numeral 18 in FIG. 14.

The portions of the conduit removal tool shown in broken lines form no part of the claimed design.
